UNITED STATES PATENT OFFICE.

ALBERT WAGNER, OF GROSS-ZSCHACHWITZ, NEAR DRESDEN, GERMANY, ASSIGNOR TO
THE FIRM FR. KÜTTNER, OF PIRNA, SAXONY.

SPINNING MACHINE FOR SPINNING ARTIFICIAL SILK.

Application filed March 16, 1927, Serial No. 175,871, and in Germany May 4, 1926.

As compared with the known device in machines for spinning artificial silk by the stretch spinning method, in which the filament passing successively through several baths is stretched progressively, the present invention is characterized by the provision of a concentric perforated drum in the can, inside which drum the spun thread is wound (instead of the spun thread lying directly against the wall of the can itself). Without the walls of the can itself having to be perforated the perforated drum according to the invention provides a large cross-sectional area for the escape of the liquid thrown by centrifugal force by the spun thread. The fact that the liquid thrown off by centrifugal force first enters the space between the drum and the can and leaves the annular space through a few outlet openings, prevents the liquid being sprayed about and the air from being saturated by the atomized liquid. Obviously the liquid will be atomized to a greater extent, if it leaves at many points in many fine jets or drops and impinges on the inside of the casing surrounding the can, than is the case, when only a few larger jets leave at a few points only and impinge on the inside of the wall of the casing. It is of great importance from the point of view of health for the atomization of the thrown out liquid to be reduced as far as possible, since the liquid thrown out is charged with acid or particles of metal salts. A further improvement, which is also important from the health point of view, is that the casing of the can is provided with soft internal lining which counteracts the scattering about or atomization of the liquid by reducing the force of impact of the jets or drops. Such a lining may for instance be made of soft rubber, preferably in the form of spongy rubber or moss rubber, or of felt. Another suitable and cheap material is wood pulp in the wellknown form of soft board. Textile fabrics or other sufficiently soft materials are also suitable for this purpose. The action of the lining is not in any way detrimentally affected by its becoming saturated with the liquid thrown out by cen-

trifugal force, as the excess of liquid continuously runs down, the essential feature being that the liquid thrown out by the can shall be prevented from striking a hard surface.

In the accompanying drawing a constructional example of the present invention is shown.

Below the drawing or stretching disc of a machine for spinning artificial silk by the stretch spinning method is a trough 23 which is continuously fed with liquid (for instance acidified water) and from which the liquid is led away by flexible tubes 24 to the thread guiding funnels 25 which are raised and lowered in the wellknown manner. The funnels which are made of glass or "Zellhorn" are surrounded by funnel shaped protective casings 26. The liquid supplied through the flexible tube 24 enters the funnels 25 at 27, thus entering the neck of the funnel together with the filaments *s*, and passes from the funnel into the can 28.

How liquid may be conveyed directly to the cans without passing through the funnels 25 need not be shown in the drawing.

The cans 28, the walls of which need only be provided at the bottom at 29 with outlet openings for the liquid thrown out by centrifugal force, are provided with sieve-like perforated inserted drums 30 which are kept centered in any suitable manner (for instance by radially interposed members). The filaments *s* lay themselves against the inner surface of the inserted drums, while the liquid which adheres to the filaments or is supplied in accordance with the invention is thrown out by centrifugal force through the perforations and at the outlets 29.

The casings 31 surrounding the cans are lined in accordance with the invention with a liner 32. At 33 the liquid caught by the casing flows out into the collecting gutter 34.

What I claim is:

1. A spinning machine for the production of artificial silk by the stretch spinning method comprising the combination with a can and a casing surrounding said can, a perforated drum positioned centrally in the

said can for receiving and enclosing the spun filaments, as and for the purpose set forth.

2. A spinning machine for the production of artificial silk by the stretch spinning method comprising in combination a can, a

for receiving and enclosing the spun filaments, and a lining in the said casing made of a soft elastic material, as set forth.

In testimony whereof I have signed my name to this specification.

ALBERT WAGNER.
